UNITED STATES PATENT OFFICE.

RALPH P. STEVENS, OF STANFORD, CALIFORNIA.

DESIGN FOR A FRATERNAL-ASSOCIATION BADGE OR SIMILAR ARTICLE.

48,333.

Specification for Design.

Patented Dec. 21, 1915.

Application filed October 30, 1913. Serial No. 798,379. Term of patent 14 years.

To all whom it may concern:

Be it known that I, RALPH P. STEVENS, a citizen of the United States, residing at Stanford, in the county of Santa Clara and State of California, have invented a new, original, and ornamental Design for Fraternal-Association Badges or Similar Articles, of which the following is a specification, reference being had to the accompanying drawing, forming part thereof.

The figure is a plan view of a fraternal association badge showing my new design.

I claim:

The ornamental design for a fraternal association badge or similar article as shown.

In testimony whereof I have hereunto set my hand in the presence of two subscribing witnesses this 13th day of October, 1913.

RALPH P. STEVENS.
